US0D1084988S

(12) **United States Design Patent** (10) **Patent No.:** **US D1,084,988 S**
(45) **Date of Patent:** **** Jul. 22, 2025**

(54) **CHARGING PILE**

(71) Applicant: **Shenzhen Yisi Technology Co., Ltd.**,
Shenzhen (CN)

(72) Inventors: **Xianjie Ni**, Shenzhen (CN); **Zibin Wu**,
ShenZhen (CN); **Zhipeng Liu**,
ShenZhen (CN)

(73) Assignee: **Shenzhen Yisi Technology Co., Ltd.**,
Shenzhen (CN)

(**) Term: **15 Years**

(21) Appl. No.: **29/918,142**

(22) Filed: **Nov. 24, 2023**

(30) **Foreign Application Priority Data**

Jul. 28, 2023 (CN) 202330477859.1

(57) **CLAIM**

The ornamental design for a charging pile as shown and described.

DESCRIPTION

FIG. 1 is a front, left and bottom perspective view of a charging pile, showing our design.

FIG. 2 is a front, right and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the charging pile that form no part of the claimed design.

1 Claim, 8 Drawing Sheets
